FIG. 4.

UNITED STATES PATENT OFFICE.

WILLIAM KRENRICH, OF BLOOMFIELD, NEW JERSEY, AND FORREST HAMMOND, OF ESSEX, CONNECTICUT.

HOLDER FOR GRAPHOPHONE-CYLINDERS.

No. 853,805.

Specification of Letters Patent.

Patented May 14, 1907.

Application filed April 13, 1906. Serial No. 311,528.

To all whom it may concern:

Be it known that we, WILLIAM KRENRICH, a resident of Bloomfield, in the county of Essex and State of New Jersey, and FORREST HAMMOND, a resident of Essex, in the county of Middlesex and State of Connecticut, citizens of the United States, have invented a new and Improved Holder for Graphophone-Cylinders, of which the following is a full, 10 clear, and exact description.

The purpose of the invention is to provide a holder for graphophone cylinders, which will be of skeleton formation and so constructed that the members or arms which come in contact with the inner faces of the cylinders are of spring material, secured at one of their ends to a support, and wherein said members are curved where they connect with the support and are from thence substantially straight but are given a slight outward inclination and are free at their lower ends, whereby as a cylinder is slid over a holder the said members or arms of the holder are gradually pressed inward and are brought in close frictional engagement with the cylinder throughout the length of their straight sections, and the cylinder is held from lateral displacement, yet may be readily placed upon or removed from the holder 30 without danger of damage.

Another purpose of the invention is to so construct the holder that it will be simple, light, durable and economic, and to provide a base or support for the holders, arranged to receive the holders and limit the movement of the free ends of their retaining arms.

The invention consists in the novel construction and combination of the several parts, as will be hereinafter fully set forth 40 and pointed out in the claims.

Reference is to be had to the accompanying drawings forming a part of this specification, in which similar characters of reference indicate corresponding parts in all the figures.

Figure 1 is a plan view of a holder and base or support therefor; Fig. 2 is a vertical section taken practically on the line 2—2 of Fig. 1; Fig. 3 is a section taken practically on the line 3—3 of Fig. 4; and Fig. 4 is a plan view of a holder applied to a modified form of base or support.

A represents the base or support for the holder B. This base or support usually con-

sists of a thin piece of wood, and wherever a 55 holder B is to be applied the base or support A is provided with an aperture 10. Each aperture 10 is either surrounded by a series of apertures 11, usually four in number as shown in Fig. 1, or is surrounded by an annular groove 12 as illustrated in Fig. 4.

The holder B consists of a post or pillar 13, which may be plain or ornamental and which may be made of wood, or other suitable material. The base 14 of said pillar or post 13 65 which rests upon the base or support A, is provided with an integral or attached dowel pin 14^a, which is fitted to the aperture 10 selected in the support A, whereby to hold the post or pillar in a firm upright position and 7c yet permit the holder to be removed from the support if desired.

The post or pillar 13 is usually provided with a head 15 or enlargement at its upper end, and this head or enlargement has by 75 preference a flat upper surface 16 upon which a designating label, such as a label indicating a number or a name may be placed, if so desired. The post or pillar 13 is provided with a series of retaining arms 17, usually four in 80 number although we do not confine ourselves to any particular number of such arms; these arms are made of reed, ratan, wire, or other spring material, and are by preference circular in cross section, and said arms may be 85 provided with a covering of a soft material if so desired. The upper end of each arm 17 is given a short regular curve a, and the upper extremities of the said arms are introduced into the enlargement or head 15 at 90 equal distances apart and are secured to the head by cement, frictional engagement, or other means.

The main or body portion a' of each retaining arm 17 is straight, but is given more or 95 less of a downward and outward inclination; and the said retaining arms 17 are of such length that their lower ends will enter the apertures 11, or the groove 12, according to the construction of the support of the holder. 100

When a holder is in position on the support A, normally the lower ends of the retaining arms 17 will be in engagement with the outer walls of the receiving apertures 11, or the outer wall of the receiving groove 12, and the 105 said groove, or the said apertures serve to limit particularly the outward movement of the retaining arms, and likewise limit their

inward movement and serve to protect the free ends of the arms.

When a cylinder C is slipped over a holder B, the retaining arms are gradually pressed inward, and as the cylinder passes by that portion of the body of the arms adjacent to the curved sections *a*, said cylinder so presses in the said arm that while the arms have constant frictional engagement with the inner 10 face of the cylinder, the cylinder when but partially entered over the holder will slowly and by gravity drop to an engagement with the support A, so that in the event the cylinder should slip from the hand while being 15 placed over a support, there will be no danger of breakage. Again, as the body or straight portions *a'* of the retaining arms have frictional engagement practically throughout their length against the cylinder, said cylinder 20 is not only well supported but is prevented from turning, or from having lateral movement, and yet the cylinder can be as quickly and conveniently removed from a holder as placed thereon.

25 The skeleton formation of the holder admits of the passage of the fingers between the arms and the post or pillar. Under this arrangement a number of cylinders may be grouped upon a support A and the support 30 constitute the bottom portion of a case, enabling the cylinders to be carried with safety long or short distances.

Having thus described our invention, we claim as new and desire to secure by Letters 35 Patent, —

1. A holder for graphophone and like cylinders, comprising a central post and retaining arms of a spring character secured at their upper ends to the post, being free at their 40 lower ends.

2. A holder for graphophone and like cylinders, consisting of a central post and resilient retaining arms having their upper portions curved and secured to the upper end 45 portion of the post and their body portions

straight but given an outward and downward inclination, the lower ends of the retaining arms being free.

3. The combination with a holder for graphophone or like cylinders, which holder 50 consists of a central post and resilient retaining arms secured to the upper portion of the post, having their upper ends curved, their lower portions straight and their lower extremities free, and a dowel extending from 55 the lower portion of the post, of a support having an opening to receive the dowel of said post and also having its upper face depressed for the reception of the free ends of the retaining arms.

4. The combination with a holder for graphophone and similar cylinders, which holder consists of a post of a rigid material having a dowel at its lower end and having 60 its upper surface flattened, and a series of resilient retaining arms having their upper ends curved and their upper extremities secured in 65 the upper portion of the said post, their major or body portions being straight and given a downward inclination, the lower ends of the 70 said arms being free, of a base or support having openings for the reception of the dowel of said posts and the free ends of the said retaining arms, whereby to hold the post stationary and limit the outward movement 75 of the arms.

In testimony whereof we have signed our names to this specification in the presence of two subscribing witnesses.

WILLIAM KRENICH.
FORREST HAMMOND.
